(57) **CLAIM**

The ornamental design for a ducted rotor, substantially as shown and described.

DESCRIPTION

FIG. 1 is a perspective view of our new design for a ducted rotor;

FIG. 2 is another perspective view of the ducted rotor as shown in FIG. 1 in an alternate configuration of use;

FIG. 3 is a side view in elevation of the ducted rotor as shown in FIG. 2;

FIG. 4 is a top plan view of the ducted rotor as shown in FIG. 2;

FIG. 5 is a front elevational view of the ducted rotor as shown in FIG. 2;

FIG. 6 is a bottom plan view of the ducted rotor as shown in FIG. 2; and,

FIG. 7 is a rear elevational view of the ducted rotor as shown in FIG. 2.

The broken lines in the drawings are for the purpose of illustrating environmental structure and form no part of the claimed design.
